UNITED STATES PATENT OFFICE.

THADIOUS V. ELLIOTT, OF BROOKLYN, NEW YORK.

FURNACE.

SPECIFICATION forming part of Letters Patent No. 746,310, dated December 8, 1903.

Application filed January 21, 1903. Serial No. 139,940. (No model.)

To all whom it may concern:

Be it known that I, THADIOUS V. ELLIOTT, a citizen of the United States, residing at Brooklyn, in the county of Kings and State of New York, have made certain new and useful Improvements in Furnaces, of which the following is a specification.

My invention is an improvement in furnaces, particularly smoke and gas consuming furnaces, and especially in that class of such furnaces in which oil, air, and steam are utilized in securing a consumption of the gases and other products of combustion; and the present invention relates to means for securing the return of the gases and smoke and a disposition thereof within the furnace; and the invention consists in certain novel constructions and combinations of parts, as will be hereinafter described and claimed.

In the drawings, Figure 1 is a perspective view of a furnace embodying my improvements. Fig. 2 is a vertical longitudinal section thereof, and Fig. 3 is a detail horizontal section on about line 3 3 of Fig. 2. Fig. 4 is a sectional plan view of the grate-bar portion of the furnace, showing a somewhat different construction from that shown in Figs. 1, 2, and 3. Fig. 6 is a detail cross-sectional view on about line 6 6 of Fig. 4. Fig. 7 is a cross-sectional view on about line 7 7 of Fig. 4; and Fig. 5 shows a modified form of air-flue, as will be hereinafter described.

In the construction shown in Figs. 1, 2, and 3 the grate-bar surface is composed of a series of hollow sections A' and A², which are similar, are open at the bottom, have their tops a perforated at a', and their sides a² fitted closely together, as shown in Fig. 1. These sections A' and A² are arranged, respectively, at the front and rear of the bottom of the furnace, the front sections A' resting at their front ends on ledges B', projecting from the rear side of the front tube B, at the lower edge thereof, as shown in Figs. 1 and 2, and at their rear ends on ledges C', projecting from the front side of the intermediate cross-tube C, at the lower edge thereof, as shown in Figs. 1 and 2. The rear tubes A² rest at their front ends on a ledge C² at the rear side of the intermediate tube C and at their rear ends on a ledge D' at the front

side of a rear cross-tube D, so the tubular grate-bar sections A' and A² are supported on ledges projecting from the tubes between which they extend and rest close together and form with the said front and intermediate tubes the bed or grate-bar surface of the furnace.

The intermediate tube C has its upper side perforated at C³ at close intervals for the free discharge of the gases, &c., supplied thereto in the manner more fully described herein-after.

The front grate-bar sections A' are each in alignment with a corresponding one of the rear grate-bar sections A², and circulating-pipes E extend from a cross-pipe F, arranged within the intermediate cross-tube C, both to the front and rear within their respective grate-bar sections A' and A², and are perforated throughout their lengths to discharge the air, steam, and oil into the grate-bar sections, as will be understood from Figs. 1 and 3. The cross-tube F has suitable couplings at F' for the connection of the discharge-pipes E and is provided at its ends at F² with couplings, to which discharge the return-pipes G for conveying the gases back to the grate-bar from the collector H, as will be more fully described hereinafter. One coupling F² also receives the discharge of the pipe I for delivering oil and steam to the cross-pipe F, such pipe I being coiled at I' at the back of the furnace and having a connection I² valved at I³ and leading from the oil-tank I⁴ and receiving the discharge from the steam-pipe J, which is valved at J', as shown in Fig. 1.

In the front of the return-feed boiler A and just above the flues thereof, as shown in Fig. 1, I provide the collector H for the gases and the like discharged by the said flues, the collector being in the form of a box or receptacle perforated at intervals to receive the products discharged from the flues and connected at its opposite ends at H' with the upper ends of the return-pipes K, which connect at K' with the return-pipes G and receive the steam-injectors L, whose pipes L' are valved at L² and which discharge downwardly in the return-pipes in such manner as to induce a suction through the collector H and a circulation thence down the pipes

G to discharge to the opposite ends of the cross-pipe F, as will be understood from Figs. 1 and 3.

In operation the unconsumed gases will be 5 collected in the collector H, discharged thence to the return-pipe, and be delivered at F² to the cross-tube C and at F' and the front tube B, as will be understood from Figs. 1 and 2 of the drawings. At the same time oil and 10 steam will be delivered to the cross-pipe F by the pipe I and be suitably controlled by the valve devices, as described and shown in the drawings.

In Figs. 4, 5, 6, and 7 I show a somewhat 15 different construction, wherein the oil and steam are delivered by pipes M, having nozzles M' and discharging within perforated flues N, extending along the opposite sides of the furnace, the return-gases discharging from up- 20 right pipes O to the front cross-pipe P, which delivers to discharge-pipes Q, as illustrated in dotted lines in Fig. 4.

In the construction shown in Fig. 4 the air-flues N open at the front of the furnace, 25 while in Fig. 7 they open at N' below the grate-bars. In both these constructions the side flues N lie in the side walls of the furnace, the oil-pipes extending into the air-pipes and having nozzles in register with the 30 openings in the air-pipe in order to send a mixture of air and oil-vapor directly into the fire over the grate. Manifestly the air-pipes may be round, as shown in Fig. 6, or square, as shown in Fig. 5. The construction shown 35 in Figs. 4 and 7, like that shown in Figs. 1, 2, and 3, includes air-pipes extending longitudinally of the furnace and having perforations, together with oil-vapor pipes, extending longitudinally within the air-pipes 40 and discharging at intervals throughout their lengths to the said pipes.

Having thus described my invention, what I claim as new, and desire to secure by Letters Patent, is—

45 1. A furnace having its grate-surface composed of front and rear series of hollow tubular sections fitting side by side, and having their upper sides perforated, front and rear cross tubular sections having projecting 50 ledges supporting the front ends of the front series and the rear ends of the rear series of sections, the intermediate cross-tube having its upper side perforated and provided with projecting ledges for supporting the adjacent 55 ends of the pipes of the sections of the front

and rear series, the cross-pipe extending within said intermediate perforated tube, the perforated discharge-pipes extending from said cross-pipe to the front and rear within the hollow sections of the grate-surface, the 60 smoke-return pipe discharging to said cross-pipe, and the oil-vapor pipe also discharging to the said cross-pipe, substantially as and for the purpose set forth.

2. In a furnace, the grate-surface having a 65 series of longitudinally-disposed perforated flues or sections combined with cross-flues communicating with said perforated flues and with means for supplying the returned smoke to one of said cross-flues and oil-vapor to the 70 other one of said cross-flues, substantially as set forth.

3. A furnace having a grate-surface consisting of a series of perforated longitudinal air-flues, and a pair of cross-flues communicating with said longitudinal flues combined with a smoke-return pipe having branches 75 discharging to said cross-flues substantially as set forth.

4. The combination in a furnace of the intermediate and end cross-flues having projecting ledges, and the hollow perforated grate-sections supported at their ends on said ledges, the cross-pipe extending longitudinally within the intermediate flue-section, the discharge-pipes leading from said cross-pipe 85 within the hollow section, and means for delivering oil-vapor to said cross-pipe, substantially as set forth.

5. The combination in a furnace, of the 90 grate-surface having an intermediate cross-flue, and a cross-pipe extending therein, means for supplying oil-vapor to said cross-pipe, the smoke-collector, return-pipes leading from said collector to the cross-pipe, and 95 injector devices operating within the return-pipes, substantially as set forth.

6. The combination in a furnace of the 100 grate-surface having front and intermediate cross-flues, and hollow perforated flues extending between the same, a cross-pipe extending within the intermediate cross-flue, a smoke-collector, and return-pipes in connection with said collector and discharging to the front and intermediate cross-flues, substantially as set forth.

THADIOUS V. ELLIOTT.
